Patented Mar. 22, 1921.

UNITED STATES PATENT OFFICE.

CALVIN JOHN FERCH, OF GRAND FORKS, NORTH DAKOTA.

HARNESS ATTACHMENT.

1,372,411.

Specification of Letters Patent. Patented Mar. 22, 1921.

Application filed January 23, 1920. Serial No. 353,491.

To all whom it may concern:

Be it known that I, CALVIN JOHN FERCH, of the city of Grand Forks, in the State of North Dakota, United States of America, have invented certain new and useful Improvements in Harness Attachments, of which the following is the specification.

The invention relates to a harness attachment and particularly to an appliance utilized for driving purposes and the object of the invention is to provide an inexpensive, efficient and durable article which can be readily attached to the harness and can be operated by the driver to prod the animal.

With the above objects in view the invention consists essentially in a swinging member fitted at one end with extending studs or prongs and provided at the other end with attaching means and a line, rope or such like for actuating the prongs, the parts being arranged and constructed as hereinafter more particularly described and later pointed out in the appended claims, reference being had to the accompanying drawing in which:—

Figure 1 is a perspective view of the device as it appears attached and in the non-operative position,

Fig. 2 is a perspective view of the article, and

Fig. 3 is a side view of a modified form of construction.

In the drawing like characters of reference indicate corresponding parts in the several figures.

1 represents a prodding member in the form of a wood block 2, which is provided on one of its surfaces with a plurality of short length prongs or sharpened studs 3.

40 The block is permanently attached to the free or lower end of a hanger or body member 4, the other end of which is attached to a fastening or attaching member 5, the fastening member being arranged to slip 45 on to the belly band 6 of the harness.

In Figs. 1 and 2 of the drawing the member 4 is shown as formed from a single piece of wire bent centrally of its length to provide a cross arm 7 and two parallel side arms 8 and 9 which have their free ends bent to provide fastening pins 10 and 11 which are driven into the sides of the block. Here it is also to be observed that the sides of the block are grooved as indicated at 12 and 55 13, the grooves receiving the ends of the

wire, thereby preventing the rotation of the block in respect to the wire and the wires are firmly held in place within the grooves by a tie wire 14 located adjacent the inner end of the block.

The member 5 in Fig. 2 is also formed from a single piece of wire bent to provide a hook like catch 15 and with the ends of the wire formed into eyes 16 and 17 which receive the cross arm 7.

From the above description it will be apparent that the side arms are pivotally connected by the eyes to the hook and that the prodding member has a natural tendency to hang down owing to the weight of the block.

In Fig. 3 where a modified form of the device is shown the wire is dispensed with and a leather strap 18 is securely fastened to the block at one end and has the other end fitted with a metal loop or ring 19 suitably riveted to the strap.

When the article, as shown in Fig. 2, is to be used it is attached to the belly band without undoing the belly band simply drawing the hook like catch over the belly band. Pulling strings 20 and 21 are attached to the side arms adjacent the block and these are connected at 22 to a single rearwardly extending pulling line 23 which passes to the driver. Here it will be observed that the point of connection 22 is located on the back of the horse. Any time the driver wishes to work the device he pulls the cord 23 backwardly, which action causes the block to swing up and the prongs to prod the underside of the belly.

The modified form of article as shown in Fig. 3 is attached to the belly band by passing the belly band through the loop and the loop is made round so that it can be readily turned on the belly band.

This article is particularly valuable where one is driving several horses, some of which are nervous or high strung. Where the ordinary whip is used one cannot whip a lazy horse without alarming the high strung horses which is undesirable. With this device any horse can be prodded without in any way alarming any of the other horses.

What I claim as my invention is:—

1. As a new article of manufacture, a prod for attaching to harness, comprising a wire body presenting a cross arm and two

parallel side arms, a block interposed between and permanently secured to the free ends of the side arms, studs extending from one face of the block and a hook like wire 5 catch pivotally secured to the cross arm.

2. The combination with a belly band, of a prodder comprising an attachment member adapted to detachably engage said belly band, a body portion, piercing studs located 10 at one end of the body, the other end being hingedly connected with the attachment member, and a pulling line associated with the last-named end for a purpose specified.

3. The combination with a belly band, of 15 a prodder comprising an attachment member adapted to detachably engage the belly band, a wire cross bar hingedly connected to the attaching member, a pair of parallel side arms extending from the ends of said cross arm, a block retained between said

parallel arms, and prongs carried by said block for a purpose specified.

4. The combination of a belly band, of a prodder comprising an attaching member adapted to detachably engage the belly band, 25 a wire cross arm hingedly connected to the attaching member, a pair of parallel side arms extending from the ends of said cross arm and at right angles thereto, a block provided with longitudinally extending 30 grooves adapted to receive said parallel arms, prongs carried by said block, and means associated with said parallel arms to retain the block in any desired position.

Signed at Grand Forks, this 10th day of 35 January, 1920.

CALVIN JOHN FERCH.
